UNITED STATES PATENT OFFICE.

AUGUST HUND, OF BETHESDA, MARYLAND, ASSIGNOR TO WIRED RADIO, INC., OF NEW YORK, N. Y., A CORPORATION OF DELAWARE.

PIEZO-ELECTRIC-CRYSTAL APPARATUS.

Application filed May 12, 1927. Serial No. 190,881.

My invention relates broadly to piezo electric crystal apparatus and more particularly to a holder for piezo electric crystal elements arranged for the production of constant frequency currents.

One of the objects of my invention is to provide a holder for piezo electric crystal elements which are arranged for the production of audible frequency currents with means for adjusting the frequency within a limited range for accurately setting the effective frequency of the apparatus.

Another object of my invention is to provide a piezo electric crystal apparatus having a plurality of piezo electric crystal elements in close association therein, with means for independently establishing connection with said piezo electric crystal elements and accurately adjusting the effective frequency of the piezo electric crystal apparatus for control of electrical circuits.

Still another object of my invention resides in the construction and arrangement of parts of a piezo electric crystal holder as described in the following specification and illustrated in the accompanying drawing in which:

Figure 1 is a cross-sectional view taken through the piezo electric crystal apparatus of my invention; Figure 2 is a cross-sectional view taken through the piezo electric crystal apparatus on line 2—2 of Fig. 1; Fig. 3 is a cross-sectional view taken through the apparatus on line 3—3 of Fig. 1; Fig. 4 shows the application of my invention to a multiple piezo electric crystal holder where adjustments may be made in the effective frequency of each of the piezo electric crystal elements for integrating the effects thereof at a predetermined frequency; and Fig. 5 is a cross-sectional view through a modified form of piezo electric crystal holder constructed in accordance with my invention.

In my copending application, Ser. No. 59,675, filed September 30, 1925, on method of producing oscillations from piezo electric plates, I have shown that comparatively small piezo electric crystal elements may be used for the production of audio frequency currents. Low frequency currents may be produced by means of a single element with a step formed in the element, or an element cut at an angle with respect to the optical axis, or a multiplicity of piezo electric crys-

tal elements which individually vibrate at a high rate of frequency differing from each other by a beat frequency may be used for integrating the effects of the several frequencies and producing a beat frequency whose alternating current is within the audible range. I have found that by varying the electrostatic coupling between the surfaces of the piezo electric crystal elements and associated electrodes that minute frequency changes may be produced which are highly desirable in effecting frequency control with a high degree of accuracy. The piezo electric crystal holder of my invention is therefore provided with means for varying the spacial relation between one electrode and the cooperating surface of the piezo electric crystal element for the selective setting of the gap between the electrode and the surface of the piezo electric crystal element to that size which will give the desired frequency in an associated work circuit.

Referring to the drawings in detail reference character 1 designates a conductive plate member upon which the insulated housing 2 is positioned by means of the screw members 3 which pass through the plate 1 and are screw threaded into the insulated housing 2. Insulated housing 2 is provided with a central bore having a plurality of differing cross-sections. The lower portion of the bore is provided with an enlarged cross-section indicated at 4. The cross-section is then reduced as represented at 5, and again enlarged as shown at 6 and internally screw threaded for receiving a retaining member 7 providing a bearing for the rotatable shaft 8 with its enlarged shoulder 9 thereon. The rotatable shaft 8 has a tubular portion 10 thereon which is internally screw threaded as indicated at 11 for receiving the screw threaded stub member 13 which carries the electrode 14 on the end thereof. The electrode 14 may be shifted vertically with respect to the upper surface of the piezo electric crystal element 40. Rotation of the electrode 14 is prevented by means of pin 15, which is arranged to slide within the pocket 16. The piezo electric crystal element 20 has its lower surface in contact with the conductive plate 1. The adjustment of the electrode 14 permits of a variation in frequency impressed upon a

work circuit from the piezo electric crystal apparatus. The piezo electric crystal element 20 is provided with a step or is cut at such an angle that current of a frequency 5 within the audible range may be generated and the integral effects of the currents generated by the different portions of the piezo electric crystal elements utilized in a circuit system which may be connected with the 10 piezo electric crystal apparatus.

In Fig. 4 I have shown separate piezo electric crystal elements designated at 21 and 22 to which electrical connection can be made by means of this adjustable device illustrated 15 in Fig. 1. The piezo electric crystal elements 21 and 22 are selected with a frequency difference equal to a beat frequency whose alternating current is within the audible range. I have shown an adjustable device 20 for establishing connection with the upper surface of piezo electric crystal element 22 which is similar to the construction of the device which establishes connection with the upper surface of piezo electric crystal element 25 21 and constructed in accordance with the structure illustrated in Fig. 1. Similar parts of the apparatus have been designated at 4', 5', 6', 7', 8', 9', 10', 11', 12', 13', 14', 15' and 16'. 30 In Fig. 5 I have shown a construction of holder for piezo electric crystal elements which cooperate to produce a relatively low frequency beat note wherein the piezo electric crystal elements 21 and 22 are mounted 35 upon metallic plate members 23 and 24 which are positioned within recesses 23^a and 24^a in the insulated base member 25 and electrically connected one with the other by means of a wire member 26 which may pass 40 through the base 25. The piezo electric crystal elements 21 and 22 are segregated from each other by means of an insulated spacer member 27 which is secured upon the insulated base member 25 by screw members 45 28 which pass through the metallic plate 29 which forms the upper contact for the top surfaces of the piezo electric crystal elements 21 and 22. The gap which is provided between the upper face of the piezo 50 electric crystals and the lower side surface of the conductive plate 29 is of the order of .2 to .3 mm., or is of such a size as may be selected for maintaining the desired control frequency in the circuits associated with the 55 piezo electric crystal apparatus.

In the piezo electric crystal apparatus where provision is made for the adjustment of the gap it will be noted that in each instance rotation of the upper electrode is prevented 60 permitting an extremely accurate setting of the gap by a movement toward or away from the upper surface of the piezo electric crystal.

The adjustable feature of the piezo electric crystal apparatus is extremely desirable

for causing a slight change or shift in the beat frequency and a change in the audio frequency tone.

In the claims I have used the expression "thickness axis" and by this I refer to an 70 imaginary line which extends perpendicularly to the upper and lower surfaces of the piezo electric element. The adjustable member in the crystal holder is aligned centrally with respect to the thickness axis of 75 the crystal holder.

The piezo electric crystal of my invention has been found to be extremely practical in construction and efficient in its operation, and while I have described my invention in 80 preferred embodiments, I desire it to be understood that modifications may be made and that no limitations upon my invention are intended other than are imposed by the scope of the appended claims.

85

What I claim as new and desire to secure by Letters Patent of the United States is as follows:

1. Piezo electric crystal apparatus comprising a metallic plate member, an insulated housing carried by said metallic plate member, and having pockets formed therein for receiving piezo electric crystal elements mounted in position upon said plate member and adjustable electrodes carried by said 90 housing centrally of each of the pockets therein for establishing an electrostatic connection with the surfaces of said piezo electric crystal elements.

95

2. Piezo electric crystal apparatus comprising a metallic plate member, piezo electric crystal elements positioned upon said metallic plate member for electrically connecting the lower surfaces of said piezo electric crystal elements, an insulated housing carried by said plate member, adjustable electrodes positioned in said insulated housing over the upper surfaces of each of said piezo electric crystal elements, said electrodes being independently adjustable with respect 105 to the upper surfaces of said piezo electric crystal elements for selectively adjusting the effective control frequency of said piezo electric crystal elements.

110

3. Piezo electric crystal apparatus comprising a connecting plate member, a multiplicity of piezo electric crystal elements having their lower surfaces in contact with said connecting plate member, an insulated housing carried by said plate member, and having pockets formed therein for centering each of said piezo electric crystal elements with respect to said plate member, and an adjustable electrode projecting through said insulated housing and into each of the 115 pockets formed therein for establishing electrical connection with the upper surfaces of each of said piezo electric crystal elements.

120

4. Piezo electric crystal apparatus comprising a conductive base member, an in- 125

130

- sulated housing carried by said base member, and having a pocket formed therein, a piezo electric crystal element having its lower surface resting in contact with said 5 conductive base member, a rotatable sleeve member journaled in said housing and having its axis centrally aligned with the thickness axis of said piezo electric crystal element, an electrode substantially conforming 10 to the shape of the upper surface of said piezo electric crystal element, and a screw threaded shank extending from the rear of said electrode and engaging said rotatable sleeve member whereby said electrode may 15 be advanced or retracted with respect to the upper surface of said piezo electric crystal element.
5. Piezo electric crystal apparatus comprising a conductive base member, a piezo electric crystal element having its lower surface resting in contact with said conductive base member, an insulated housing carried 20 by said base member, and having a pocket formed therein for receiving said piezo electric crystal element, a rotatable member journaled in said housing and having its vertical axis coincident with the thickness axis of said piezo electric crystal element, said rotatable member being internally screw threaded, an electrode substantially conforming 25 to the shape of the upper surface of the piezo electric crystal element, a screw threaded shank extending from the rear of said electrode and engaging the internally screw threaded rotatable member, means extending between said electrode and said housing for preventing rotary movement 30 of said electrode while permitting the advancing or retracting thereof for adjusting the gap between said electrode and the upper surface of said piezo electric crystal element. 35
- In testimony whereof I affix my signature.
- AUGUST HUND.
